Communication dated Jun. 22, 2015, issued by the Japan Patent Office in corresponding Japanese design application No. 1484218.

Primary Examiner — Stacia Cadmus

(74) *Attorney, Agent, or Firm* — Sughrue Mion, PLLC

(57) **CLAIM**

The ornamental design for a tread portion of an automobile tire, as shown and described.

DESCRIPTION

FIG. 1 is a perspective view of a tread portion of an automobile tire according to my design;
FIG. 2 is a front view thereof;
FIG. 3 is a top view thereof;
FIG. 4 is a right side view thereof;
FIG. 5 is a left side view thereof;
FIG. 6 is a rear view thereof;
FIG. 7 is a fragmentary enlarged front view showing the details of the tread portion thereof;
FIG. 8 is a section view taken along line 8-8 in FIG. 7;
FIG. 9 is a section view taken along line 9-9 in FIG. 7; and,
FIG. 10 is a section view taken along line 10-10 in FIG. 7.
The broken lines are used to show portions of the tire that are not being claimed, and thus form no part of the claimed design.

1 Claim, 10 Drawing Sheets
